UNITED STATES PATENT OFFICE.

FRED L. MACKENZIE, OF BEVERLY, MASSACHUSETTS, ASSIGNOR TO UNITED SHOE MACHINERY COMPANY, OF PATERSON, NEW JERSEY, A CORPORATION OF NEW JERSEY.

TACK-PULLING MACHINE.

1,109,238.

Specification of Letters Patent.

Patented Sept. 1, 1914.

Application filed January 11, 1911. Serial No. 601,953.

To all whom it may concern:

Be it known that I, FRED L. MACKENZIE, a citizen of the United States, residing at Beverly, in the county of Essex and State of Massachusetts, have invented certain new and useful Improvements in Tack-pulling Machines; and I do hereby declare the following to be a full, clear, and exact description of the invention, such as will enable others skilled in the art to which it appertains to make and use the same.

The present invention relates to tack pulling machines, and more particularly to machines employed for removing the lasting tacks from a shoe prior to the sewing operation.

Machines of this general character are provided with tack pulling jaws which are advanced into a tack engaging position to engage the head of the tack, and then are retracted in an inclined plane to pull the tack. The jaws are supported to move toward and from one another and means are provided for moving the jaws to engage and release the tack at proper intervals.

The object of the present invention is to improve the construction and mode of operation of machines of this type. With this object in view a feature of the invention 30 contemplates the provision of a rotary cam for actuating the tack pulling jaws provided with working faces which are normal at their point of operation to the inclined plane in which the jaws are retracted and which are inclined to the axis of the cam.

A further feature of the invention comprises a plurality of slides which are adapted to move substantially at right angles to the faces of the cam for imparting an advancing and retracting movement to the jaws, and an auxiliary slide which is slidably supported in one of the first mentioned slides and operated by the same cam to impart an oscillatory movement to one of the 40 jaws.

Other features of the invention comprise certain novel constructions and arrangements of parts hereinafter described and claimed, the advantages of which will be 50 obvious to those skilled in the art.

In the drawings illustrating the preferred form of the invention Figure 1 represents a side elevation of the improved tack pulling machine with certain parts of the machine 55 cut away and shown in section. Fig. 2 is

an end elevation of the machine looking at the same from the front. Fig. 3 is a detail showing an elevation of the operating mechanism for one of the jaws. Figs. 4 and 5 are detail views illustrating the mode of operation of the jaws and Fig. 6 is a diagrammatic illustration of the path of movement of the tack engaging ends of the jaws.

The present machine is designed as an improvement upon the machine illustrated in the application for United States letters patent of Hadaway, No. 498,238, filed May 25, 1909.

In the illustrated embodiment of the invention the tack pulling devices consist of two tack pulling jaws 1 and 2, which are moved toward and from the work in engaging and pulling a tack. The work is supported during the pulling operation by engagement with a work support 3 against which the shoe is held by the operator.

The machine is also provided with a second work support or guard 4 arranged to engage the upper on the inner side of the row of lasting tacks. The work support 3 is attached to the outer end of a throat 6 which projects integrally from the machine frame 7, and the work support and throat together form a passage-way or a chute through which the tacks may be discharged. The guard or work support 4 is provided with a projecting finger 8, shown in Fig. 2, which engages the lower front edge of the work support 3 and forms a tack engaging stop at the outer end of the throat between the adjacent edges of the work supports through which the tack is guided into position to be acted upon by the tack pulling jaws. The guard or work support 4 is adjustably secured to the end of a supporting arm 9 so that it may be properly adjusted with relation to the work support 3 and the ends of the jaws when they are in tack engaging position.

The shoe is presented to the machine with the line of lasting tacks extending parallel with the tack engaging edges of the tack pulling jaws so that the work supports 3 and 4 bear upon the upper on both sides of the line of tacks as the tacks are brought successively into position to be engaged by the jaws. In operating upon the tacks, the tack pulling jaws are advanced until the tack engaging ends project into, or slightly beyond, the plane of the upper when held

against the work supports 3 and 4 and are then closed to engage the opposite sides of the tack, and are then retracted to withdraw the tack from the shoe, the jaws being 5 again opened or separated before or during the next succeeding advance movement toward the upper. After the tack pulling jaws have been retracted to withdraw the tack from the shoe, a relative movement is 10 imparted to the jaws to forcibly eject the tacks carried thereby.

In the construction shown, the upward movement of the jaw 1 ceases after the tack has been pulled, while the upward movement 15 of the jaw 2 is continued. This upward movement of the jaw 2, with relation to the jaw 1, carries the tack up along the front face of a shoulder 10 formed upon the jaw 1 until the tack passes the upper edge 20 of the shoulder, when the pressure on the rear side of the tack being thus removed, it is ejected to the rear, as indicated clearly in Fig. 5. After the tack has been ejected, the jaws are separated or opened and are 25 again advanced so that they are brought simultaneously into tack engaging position and are simultaneously engaged with the tack and retracted. The path of movement of the tack engaging jaws is indicated 30 clearly in Fig. 6.

It is customary in machines of this character, in order that the lasting tacks may be properly pulled, to retract the jaws in an inclined path, and in the preferred embodiment of the invention this is accomplished by supporting the jaws upon a plurality of slides which are caused to move parallel to the line of retraction of the jaws. In order that the jaws may be opened and closed, they 35 are supported for oscillatory movement upon the slides. A single cam operates the slides to advance and retract the jaws and also imparts an oscillatory movement to one of the jaws, and a second cam is provided to oscillate the other jaw through suitable connections. This produces an extremely simple and efficient method of imparting the proper movement to the jaws and with a relatively small number of 40 parts. In order to accomplish this end, the jaw 1 is pivotally supported upon the lower end of a slide 11 and the jaw 2 is pivotally supported upon the lower end of a slide 12. The slides 11 and 12 are slidably mounted 45 in guideways formed in the opposite faces of a block 13 which is fixed to the machine frame in an inclined position in order that the slides shall move parallel to the jaws when the latter are retracted. The slides 50 are retained in their respective guideways by a plurality of cover plates 14 fastened to the opposite faces of the block 13 and all wear upon the slides and guideways is taken up by wear plates 15 which are ad- 55 justed by a plurality of adjusting screws 16.

The block 13 is conveniently retained in position by a plurality of clamp bolts 17 and is provided with a dove-tailed face engaging a corresponding face formed upon the machine frame in order to prevent the 70 block from turning relatively to the machine frame.

In order to provide for an adjustment of the jaw 1 to and from the work supports, it is adjustably mounted in a holder 18 75 which is formed as a bell-crank lever and is pivoted to the slide 11 at 19. The jaw 2 is also adjustably mounted in a holder 20 which is in the form of a curved lever pivoted upon the slide 12 centrally at 21. The slides 11 and 12 are reciprocated to advance and retract the jaws and at the same time oscillatory movements are imparted to the holders 18 and 20 in order to open and close the jaws. The slides are reciprocated 80 at the proper time by a cam 23 which is mounted upon the main driving shaft 24 journalized horizontally in the upper portion of the machine frame.

It will be noted that the planes in which 90 the slides are retracted are inclined to the axis of the cam 23 and in order to reciprocate the slides in the most efficient manner, it is essential that the working faces of the cam be normal at their respective points of 95 operation to the planes in which the slides move. In the preferred embodiment of the invention, the cam 23 is provided with a plurality of cam grooves, the sides of which are normal at their points of operation to 100 the path of movement of the slides and may aptly be termed the working faces of the cam. In order to enable the slides to move in close proximity to the respective working faces of the cam, the cam 23 is provided with 105 the conical faces 26 and 27 which are parallel to the plane in which the jaws are retracted. The conical face 26 has the cam grooves 28 and 29 formed therein and the conical face 27 is provided with the cam 110 groove 30. The slide 11 is provided with a cam roll 32 which engages with the cam groove 28 and the slide 12 is provided with the cam roll 33 which engages with the cam groove 30 in order to advance and retract 115 the jaws at the proper intervals. The cam 23 is also conveniently employed for imparting an oscillatory movement to the jaw 1 and for this purpose an auxiliary slide 34 is employed which is slidably mounted in 120 guideways formed in the slide 12. The slide 34 is connected to one arm of the holder 18 by a link 35 and is reciprocated relatively to the slide 12 by the cam groove 29 which is operatively connected to the slide by means 125 of a roll 37. An oscillatory movement is imparted to the jaw 2 by a cam 38 mounted upon the drive shaft 24. The cam 38 is provided with a cam groove 39 which engages with a cam roll 40 mounted upon the upper 130

end of a lever 41. The lever 41 is pivoted centrally upon an arm 42 projecting laterally from the machine frame and is connected at its lower end to the upper end of the holder 20 by means of a link 43.

While it is preferred to employ the specific construction and arrangement of parts shown and described, it will be understood that this construction and arrangement may 10 be changed and modified without departing from the broader features of the invention.

What is claimed is:—

1. A tack pulling machine, comprising a work support, a pair of tack pulling jaws, 15 means for advancing and retracting the jaws comprising a rotary cam provided with working faces which are normal at their point of operation to the plane in which the jaws are retracted, a plurality of slides 20 supporting the jaws and adapted to move parallel to the said plane, and operative connections between the cam and slides, substantially as described.

2. A tack pulling machine, having, in 25 combination, a work support, a pair of tack pulling jaws, means for advancing and retracting the jaws comprising a rotary cam having a plurality of conical faces parallel to the plane in which the jaws are retracted, 30 cam grooves formed in the conical faces and having their working faces normal to the plane at their points of operation and operative connections between the cam and jaws, substantially as described.

35 3. A tack pulling machine, having, in combination, a work support, a pair of tack pulling jaws, a slide supporting each jaw, a rotary cam adapted to reciprocate the

slides to advance and retract the jaws, the slides being adapted to move parallel to the 40 plane in which the jaws are retracted, an auxiliary slide supported upon one of the first mentioned slides and operated by the rotary cam to oscillate one of the jaws, and a second rotary cam operatively connected 45 to the second jaw and adapted to oscillate it at the proper intervals to open and close the jaws, substantially as described.

4. A tack pulling machine comprising a pair of jaws having a tack pulling movement in an inclined plane, a slide carrying 50 each jaw and moving parallel to the plane of the tack pulling movement, and a single rotary cam for imparting a tack pulling movement to both jaws, substantially as described. 55

5. A tack pulling machine comprising a tack pulling tool, a drive shaft, a rotary cam mounted thereon having a face arranged obliquely to the drive shaft and provided with a cam groove, and operative connections between the rotary cam and tack pulling tool, substantially as described. 60

6. A tack pulling machine having, in combination, a pair of coöoperating tack pulling 65 jaws, a slide supporting each of the jaws, an actuating cam connected to the slides to impart advancing and retracting movements to the jaws, and connections between the cam and one of the jaws to move it toward and 70 form the second jaw, substantially as described.
